APPARATUS FOR GRINDING CULTIVATOR DISKS

Andrew J. Harty, near Bradford, Ill.

Application July 8, 1946, Serial No. 681,895

17 Claims. (Cl. 51—106)

1

This invention pertains to machines for grinding and polishing harrow discs, while adapted for other grinding purposes.

An object of the invention is to provide a machine so arranged that a gang of discs removed from a cultivator-frame may be lifted bodily to a position at a grinding wheel where each disc of said gang may be sharpened.

Another object is to provide a machine with mechanism to engage a gang of mounted discs and station it in position for applying a grinding wheel or a polishing wheel to each disc separately, and to provide for automatically handling any such wheel for grinding or polishing.

Still another object is to provide a structure including a suspended grinding wheel which may be supported above and shifted in a direction paralleling a shaft upon which is mounted a series of discs as removed from a cultivator so that each separate disc so mounted may be ground and conditioned for further work in the field.

Again an object is to erect a carrying frame for supporting a driven grinding wheel that may be tilted on a horizontal axis above a series of shaft-mounted cultivator-discs whereby said wheel can operate separately upon each of the several discs, the wheel at the same time being so suspended, also, that it may swing from the frame parallel to the series of discs so mounted.

Other objects and advantages will be apparent in the following description aided by the appended drawings forming part hereof, wherein

Figure 1 is a plan of the machine of the present invention.

Figure 2 is a side elevation of a spanner bearing illustrated in said Figure 1.

Figure 2^a is an elevation of part of a disc-shaft support in section showing a shaft with its disc supported thereon.

Figure 3 is a longitudinal section of a universal joint or chuck.

Figure 3^a is a transverse section of said joint or chuck produced on line 3^a of Figure 3.

Figure 4 is a side elevation of the machine as viewed from the left of Figure 1.

Figure 4^a is a vertical section of a housing, and parts carried thereby.

Figure 5 is a front elevation of the same as viewed from the right of Figure 4.

Figures 5^a and 5^b are, respectively, a longitudinal section in elevation, and an end elevation of a locking structure shown in Figure 5.

Figure 6 is an enlarged view in part section of a hanger structure shown in Figure 5.

Figure 7 is an enlarged transverse section of a 55

2

member of a rocking frame shown in Figure 5 and a roller supported structure thereon.

Figure 8 is a sectional view in elevation of part of the wheeled supporting frame shown in Figure 4.

Figure 9 illustrates in perspective a structure illustrated in said Figure 8.

Figure 10 is a side elevation of operating parts as viewed from the right of Figure 5, and

Figures 11 and 12 are, respectively, a side elevation and a plan of a mechanism illustrated in plan in Figure 1.

As distinguished from the known art the machine of the present invention provides for lifting from the ground a disc-gang which has been removed from a disc harrow and placing it adjacent a grinding wheel where the latter by a special mounting can travel from end to end of the usual disc shaft so that all of the several discs thereon may be processed at one operation. That this may be done the shaft is coupled with a driving mechanism for rotation with respect to the driven grinding wheel, the latter being so mounted that it may be either manually applied to each disc at either side thereof, or automatically made to process the discs as will appear.

Again, while the machine is primarily adapted for disc grinding, or for polishing or buffing, it is also so constructed that the grinding wheel may be adjusted for use as a "bench" tool for other grinding purposes, all of which will appear herein together with advantages of certain structures and the operation thereof.

In the drawings 1 denotes a pair of spaced supporting sills upon which at what will be termed the "front" of the machine, is secured a rod or pipe 2 lying in a transverse position, while a rod or pipe 3 is likewise so placed near the rear ends of said sills as in Figures 1 and 4, the whole constituting a platform.

Erected upon the pipe 2 and secured thereto at each end is a standard 4, Figure 5, suitable braces 5 connecting said standards with the pipe 3, for example, whereby the standards are stabilized.

The upper ends of the standards 4 in this instance, have right angled extensions 6. Beneath the extensions is a rectangular frame 7 preferably long and narrow as in Figure 1, and serving as a runway for a carriage to be described, said frame at its narrow extremities being each supported midway thereof by hangers 8 enclosing said extremities of the standards.

In this manner said frame is free to rock or

tilt vertically for a purpose to appear. Suspended within the frame 7 is a carriage 9 as a housing for an electric motor 7', said carriage having a stud 10 extending from each of two opposite sides, each stud being carried by and rockable in a pair of plates 12, said plates being mounted upon a pair of spaced tandem rollers 11 resting upon and to travel along one of the relatively long members of the frame 7. The plates 12 form a housing enclosing the frame members 7 to retain the rollers 11 on the latter in the tilting or rocking movement of the carriage. Depending from the carriage 9 is a shaft 13, Figure 5, carrying a grinding wheel 14, said shaft being driven by the electric motor 7'.

Mounted in fixed position upon the carriage 9 is a member 11' parallel to the longest measurement of the frame 7. This is provided with a series of holes 112, for example, by which a weight 113 may be secured by a pin 114 in any desired position. Said weight when shifted in either direction along the member 11' will tend to swing the grinding wheel in one direction or the other during grinding operations.

It is now evident that since the frame 7 is tiltable laterally, and that the carriage 9 is tiltable on the said frame as permitted by the studs 10 in the plates 12, the grinding wheel is free to swing in all directions.

As shown in Figure 5 a frame 15 is mounted on the rod or pipe 2 at the front of the structure. This frame, as in Figure 1, is, in this instance, of a U form, the extension being mounted to rock upon said pipe. These said extensions, as best shown in Figure 4, are upturned beneath the position of the freely suspended grinding wheel. The extremities of the frame at this position are recessed at 16, see Figure 2^a, and a pair of spaced rollers 17 lie therein in such positions as to receive upon them the shaft A of a gang of discs, one of which is denoted at B in the figure last named. Further, forward of the recess 16 and said roller 17 each of the frame portions 15 has an upwardly-extended forwardly-curved finger 18.

Also mounted to swing about and terminating at the pipe 2 is a second frame 19, Figures 1, 4 and 8. This frame is also of a U-form, in this instance, and is therefore much like the frame 15 but lies within the latter and beneath the same at the rear thereof and attached thereto by bolts X, for example. Said frame has control of the frame 15 so that when it is raised to the broken line position in Figure 4 the latter will also be raised to project outwardly the extremities having the fingers 18. Said fingers in the extended position will receive the shaft A of the disc gang as the latter is rolled toward them, whereupon by depressing the said frames 15 and 19 the gang will be elevated to position at said grinding wheel.

In order to support the separately extending extremities of the frame 15 in a rigid manner a structure shown in Figures 8 and 9 is provided merely as an instance of what may be employed. That is to say, beneath the frame 19 is a rod 20 lying across and secured upon the sills 1. Depending from said rod is a hanger 21 just below each of the parallel extensions of said frame. Each hanger is provided with a slot 22. Within the slot lies a bar 23 notched at 24 on its lower edge near one end to engage the hanger within said slot 22. The other end of the bar is pivoted at 25 to the frame 19. A spring 26 constantly under a pulling tension is connected to and between the bar 23 adjacent the pivot 25 and the hanger 21. When the frames 15 and 19 lie as in Figure 4 75 instance, a sliding bearing 45 is provided denoted

the notch 24 receives the edge of the slot 22 so that any tendency of the load of discs upon the frame 15 to swing forwardly and downwardly the upright extensions of the latter will be thwarted.

When, however, the frames 15 and 19 are to be lifted to pick up the load from the ground (dotted lines Figure 4) a trip arrangement is employed. This may consist of a rock shaft 27 carried in the hanger and to which is secured a foot-lever 28. Said shaft is provided with a finger 29 at each of the two bars 23, Figures 1 and 9, so that by pressure on said foot-lever the two bars 23 will be disengaged from the hangers permitting the said frames 15 and 19 to be lifted. The springs 26 when greatly extended by raising the frames 15 and 19 will assist in lifting the picked up load when the frames 15 and 19 are again lowered.

In order to properly grind the discs of the supported gang some means of rotating the discs is required. Therefore, mounted in a bearing 30 fixed with respect to a sill 1, see Figure 5, is a shaft 31 centered with the shaft of the disc-gang. This shaft is driven by a wheel 31 belted to the pulley 32 of a power unit 33. Said shaft as shown in Figure 3 may have a squared socket 34 to receive a squared stub-shaft 35 which extends into a tubular member 36 having a squared recess 37. The stub-shaft has a pin 38 extending from each of its four sides, and these extend through slots 39 in the walls of said member 36 while springs 40 encircle the pins between said walls and said stub-shaft.

In the open end of the tubular member 36 may be inserted the end of the shaft A for the discs B, said shaft at its end usually having a square portion 41 to which the recess 37 is adapted.

By this, or an equivalent arrangement it is clear that a positive drive for the shaft A is assured even though the axes of the shafts do not coincide.

Means is provided for maintaining engagement of the disc-shaft A with the tubular member 36. In Figures 1, 4 and 5 a standard 42 is erected on a sill 1. Affixed to the standard is a notched plate 43 upon which is pivoted a lever 44 carrying any usual latch 45 for adjustment purposes. Said lever carries a roller 46, Figure 1, which may be engaged with a disc near its center of rotation, the proper setting of the lever serving to hold the shaft A of the discs in permanent driven engagement with the tubular member 36.

It has long been conceded that the proper manner of sharpening a cultivator disc is to apply the grinding element to the convex side of said disc and work toward the cutting edge thereof. The advantage of the present structure is at once realized. That is to say, since the grinding wheel is so mounted as to be swung in all directions it can be used to provide the described preferred manner of sharpening. Further, the wheel can be swung in contact with either the convex or concave side of the disc without hindrance and thereby the whole disc can be cleaned to provide a bright surface as required for proper working in the field.

Since the carriage 9 carrying the shaft 13 of the grinding wheel 14 is free to swing, as before stated, said wheel may be employed in grinding for purposes other than disc treatment. As will be noted in Figure 5 in broken lines the grinding wheel 14 may be swung with said carriage 9 so that the said grinding wheel 14 may rotate in a vertical plane. In order that the shaft 13 may retain a substantially horizontal position, in this 70 instance, a sliding bearing 45 is provided denoted

in continuous lines in Figures 1 and 4, see also Figure 2. This may include a pair of U-bolts 45² to engage beneath the side rails or members of the lifting frame 7 which may be removed or placed in position as occasion demands. In Figure 5 this bearing 45¹, which is slidably mounted upon the long rails of the frame 7, is removed from the continuous line position and replaced at the broken line position to support the said shaft 13. In order that the grinding wheel 14 may be conveniently used as a "bench" tool the entire machine may be tilted forwardly as shown in broken lines in Figure 4, the carriage 9 and the wheel being placed in a convenient position for use. At such time the disc-supporting extension of the frame 15 being out of the way since said frame, rearwardly, may lie close to the sills 1 as in continuous lines in the drawing-figure last named. Means are provided for fixing the mountings of the carriage in respect to the rails of the said frame whenever required for a stationary grinding position. This means, of which there are two, shown in Figures 1, 5, 5^a, and 5^b may each consist of a housing 46¹ of U-form, for example, each of which is normally slidable upon a rail. Between the extensions of each housing is a friction block 47 spaced from which is an arm 48 pivoted at one end to said housing. Abutting the under side of the free end of the arm is a rocking arm 49 extending from a shaft 50 extending between and journaled in both housings 46¹. Finally, a compression spring 50¹ is interposed between the arm 48 and the named friction block.

It may be thus seen that by rotating the shaft 50 each of the two blocks may be made to either grip a rail of the frame 7 or release it. The two housings 46¹ are connected with the mountings 12 for the carriage 9 by links 51 pivotally connected to each. When the rails are thus gripped the carriage 9 is prevented from shifting along the rails when it is desired to manually swing said carriage on its studs 10 at a fixed point. In this connection it is to be noted in Figures 4 and 5 that a stabilizing frame 9¹ for the grinding wheel shaft 13 is secured to the carriage and from the extremity of said frame extends horizontally a rod 9², Figures 1 and 4 having a cross arm 9³ which latter, when gripped by the operator, serves to swing the grinding wheel to any position desired.

It has been heretofore intimated that the operation of grinding the discs B may be either manual or automatic. Mechanism is now made known for the latter method. The previously described shaft 30¹ driven by motor 33 is provided with a pulley 30² belted to a wheel 51¹, Figures 1 and 10. Said wheel is affixed to a shaft 52 having a bearing in a plate 53 secured in this instance to an upright member 4 of the mechanism. Said shaft 52 carries a plate 54 provided with a stud 55 spaced from the center of plate rotation, the plate 50 and stud serving as a crank, as will be seen. Carried by said stud 55 is a frame including in this instance a pair of parallel arms 56 forming a U. Affixed to and spanning the space between the arms is a portion 57 through which extends a thread bar 58, the latter extending from the closed end of the U-member 56 and provided with a crank 59. The thread bar rotates within the portion 57 without results and is prevented from traveling therein by collars 60 fixed to said thread bar. The free end of the thread bar has engagement, however, with an arm 61, the latter, therefore, in the rotation of the thread bar increasing or decreasing the distance between itself

and the stud 55 for a purpose to appear, it being understood that since the thread bar 58 may rotate within the portion 57 it has endwise movement in the arm 61, thus changing the distance between said portion 57 and the said arm 61 with which it has threaded engagement.

Secured to and depending from the frame 7, Figures 1, 4 and 10 is a rod 62 having a crosspin 63 therein which projects from opposite sides thereof as best shown in Figure 12. The arm 61 carries on its underside a saddle member 64 adapted to receive one extremity of said pin 63 into it, a weight 65 on the arm normally preserving their engagement.

Mounted to tilt on the opposite end of the pin 63 is a hand lever 66 one end of which carries a pin 67 to engage beneath the arm 61 as in Figure 12. A compression spring 68 on the pin 63 between the depending rod 62 and the lever 66 serves, by friction, to hold the saddle member 64 above and free of the pin 63 when the said arm 61 is lifted.

When the motor 33 is in operation the belt wheel 51¹ is always in operation together with a reciprocating motion imparted to the arm 61. During such reciprocations of the latter no action is imparted. However, during such movements the depending rod 62 will be swung in opposite direction when the saddle member 64 is resting upon the pin 63. In this event the frame 7 will be tilted in opposite direction as the stud 55 of the plate 54 moves through its orbit. Naturally, cessation of this movement results when the hand lever 66 is operated to lift said arm 61. The degree of swing of the depending rod 62 is governed by the adjustment of the thread bar 58 as explained earlier.

The purpose of swinging or tilting the frame 7 is that when such as a wire brush is substituted for a grinding wheel the entire opposite surfaces of each disc B may be traversed by the brush as suspended from said frame 7. The adjustment at the thread bar 58 is such that discs of various diameters may be processed.

During the removal of rust from the disc, and the somewhat polishing action on the same the automatic action is assisted by shifting the weight 11³ of the carriage to such a position that the brush will be forced in the direction of the surface being treated.

By the slow rate of rotation of the crank pin 55 due to the difference in size of the pulleys 32—30² as compared with the size of the wheels 31—51¹ the tilting action of the frame 7 is quite slow so that the swinging movement of the rapidly rotating wire brush over the disc surfaces is quite slow, while at the same time the rate of rotation of the discs is also slow.

In Figures 4 and 5, particularly, an arrangement is shown which will either secure the frame 7 with respect to a standard 4, or permit the tilting action just described, depending upon whether the operator desires a fixed condition during manual handling of the grinding wheel, or automatic action when employing the wire brush.

A structure not unlike that described in respect to what is shown in Figures 11 and 12 is employed for the above purpose. In this case the U-shaped structure denoted at 56¹ corresponding to the structure 56 is attached at one end to the frame 7 by a link 69, while at its other end it is attached by a link 70 to a lever 71 pivoted to a notched member 72 secured on the standard 4, said lever having any usual latch 73 to engage said notched member.

When the latch is engaged with a notched member 72 tilting of the frame 7 is prevented but when disengaged the frame is free to tilt. In the latter case a link 74 on the lever serves to engage over the latch arrangement to hold it in disengaged position. In this latter position of the latch the frame 7 in tilting will merely swing the lever 71 vertically in a free fashion.

Throughout the foregoing certain structures have been described for use but naturally equivalent means may be employed so long as the purpose of the several mechanisms are realized.

Since the machine is wheel mounted it is transportable so that it may be used in the field or shop.

When a gang of discs is to be sharpened or polished the foot lever 28 is depressed to lift and release the rods 23 at the hangers 21, while also grasping the frame 19. Thereupon said frame is lifted together with the frame 15 and thus the fingers 18 of the latter are swung downwardly and forwardly to a position to receive the shaft A of the discs as in broken lines in Figure 4. Then by moving the frames to their original positions shown in said figure the forward extremities of said frame 15 will take the upright position, carrying the disc-gang with them, said shaft A naturally dropping by gravity upon the supporting rollers 17 therefor.

At this time the said rods 23 again engage the hangers 21 thus supporting the disc-shaft in working position. As this occurs the named shaft has been presented to the universal joint or chuck 36, whereupon the lever 44 carrying the wheel 46, Figure 1, is shifted in a direction to force said wheel 46 against an adjacent disc B and through said disc shift the shaft into said chuck in driving relation therewith. Starting the motor 33, of course, will set the discs in rotation. Upon starting of the motor 7' within the carriage 9 the grinding wheel or brush, as case may be, is set in rotation and by means of the control structure 92, 93 the wheel may be urged against any desired disc, this being possible due to the freely swinging carriage, and the ability to shift the latter along the frame 7. And as an aid to the operator in swinging the carriage in a given direction the weight 113 on said carriage may be shifted to that position on the bar 111 that will most help such operator in any tilt given said carriage. During these operations of hand grinding the frame 7 may be allowed to tilt on the standards 4, or prevented from doing so by employing the mechanism 56, 71, 72 at the right of Figure 4.

If, now, the machine is to operate in an automatic manner the parts shown in Figures 10, 11 and 12 may be employed. As already stated, the belted mechanism in Figure 10 is always in operation when the motor 33 is in action. If the arm 61 is not operatively engaged with the pin 63 on the rod 62 of Figure 11 it may be allowed to lower by moving the lever 66. This done, the part 64 which is always in motion endwise due to the travel of the crank-pin 55 of the rotating plate 54, will transmit a slow rocking movement to the frame 7 by reason of the swing of the said rod 62 imparted by said arm 61. In such event, of course, the said rocking mechanism 56, 71, 72 is permitted free movement with the said frame 7 by latching the link 74 of that mechanism upon the then disengaged latch 73. Since the frame is now rockable the carriage 9 will rock with it and therefore the abrading wheel, which in this instance may be a wire brush, can be placed against any disc surface to clean that surface of

rust. Any disc will be traversed from periphery to near its center as the brush thus swings with said frame. At this time the carriage 9 may be so located on the frame that its weight will hold the brush to its work aided by the adjusted weight 113, the entire series of discs being thus worked upon.

If discs of different gangs are of various diameters it is clear that the adjustment of the thread bar 53 of Figure 11 will serve to increase or decrease the distance of brush travel in accordance with disc diameter.

When the abrading wheel 14 is to be used as at a bench, for example, by rotating in a vertical plane, see broken lines in Figure 5, the entire machine may be tilted forwardly as in Figure 4 (broken lines) thus carrying the carriage clear of the machine for close-up work of the operator, and by shifting the bearing 45' along the frame 7 to the broken line position to support the shaft 13 the mechanism is in condition for various grinding operations. When so used the parts 92, 93 may be removed from the carriage to be out of the way of such operator.

I claim:

1. In apparatus of the type described, a supporting frame, a suspended rotatable abrading wheel carried by the frame, means supported on the frame adapted to swing in a vertical plane downwardly to a position to receive upon it the shaft of a cultivator disc-gang, said means adapted for moving the received disc-gang to a position adjacent said wheel for receiving abrading action of the same upon a disc of said gang.

2. In apparatus of the type described, a supporting frame, a suspended rotatable abrading wheel carried by the frame, means supported on the frame adapted to swing in a vertical plane downwardly to a position to receive upon it the shaft of a cultivator disc-gang, said means adapted for moving the received disc-gang to a position adjacent said wheel for receiving abrading action of the same upon a disc of said gang, and means for positively maintaining the first said means in a position during the action of said wheel upon said disc.

3. In apparatus of the type described, a supporting frame, a suspended rotatable abrading wheel carried by the frame and capable of swinging movement in all directions, means supported on the frame adapted to swing in a substantially vertical plane between two extreme positions and in one of its positions adapted to receive thereon a cultivator disc-gang and in another position adapted to hold the disc-gang in a position to receive the rotating abrading wheel upon the disc surfaces.

4. In apparatus of the type described, a supporting frame, a suspended rotatable abrading wheel carried by the frame and capable of swinging movement in all directions, means supported on the frame adapted to swing in a substantially vertical plane between two extreme positions and in one of its positions adapted to hold the disc-gang in a position to receive the rotating abrading wheel upon the disc surfaces, and means to rotate the disc-gang when the same is in the second named position.

5. In apparatus of the type described, a supporting frame, a suspended rotatable abrading wheel carried by the frame and capable of swinging movement in all directions, means supported on the frame adapted to swing in a substantially vertical plane between two extreme positions and in one of its positions adapted to hold the

disc-gang in a position to receive the rotating abrading wheel upon the disc surfaces, means to rotate the disc-gang when the same is in the second named position, and means for positively sustaining said means in the last named position.

6. In apparatus for the purpose described, a framing, means mounted on the framing swingable in a substantially vertical plane from a substantially horizontal position to a substantially upright position and adapted to carry a cultivator disc shaft having a series of discs thereon, means engageable with and adapted to rotate said shaft, a support carried by the framing, and a driven rotatable abrading wheel suspended from and adapted to move along said support substantially parallel to said shaft in close relation to the named discs.

7. In apparatus for the purpose described, a framing, means mounted on the framing swingable in a substantially vertical plane from a substantially horizontal position to a substantially upright position and adapted to carry a cultivator disc shaft having a series of discs thereon, means engageable with and adapted to rotate said shaft, a support carried by the framing, and a driven rotatable abrading wheel suspended from and adapted to move along said support substantially parallel to said shaft in close relation to the named discs, and means to fix the first named means in its upright position.

8. In apparatus for the purpose described, a framing, means mounted on the framing adapted to swing between two extreme positions in a substantially vertical plane, said means in an extended position adapted to receive thereon the shaft of a cultivator disc-gang and adapted also when moved to another position to lift said disc-gang and to support it in a freely rotatable position, means to engage and rotate said shaft of said disc-gang in its lifted position, a support carried by the framing, and a rotatable abrading wheel depending from the support arranged to shift in a plane substantially paralleling said shaft of said gang.

9. In apparatus of the character described, a framing, a tiltable structure supported on the framing constituting a runway for a carriage, a carriage mounted on the structure adapted to shift along the same, a mounted and driven abrading wheel depending from the carriage, mechanism connected with and for automatically tilting the structure, and a support for carrying the shaft of a cultivator disc-gang, said shaft substantially paralleling the direction of shift of said carriage on said structure.

10. In apparatus of the character described, a framing, a tiltable structure supported on the framing constituting a runway for a carriage, a carriage mounted on the structure adapted to shift along the same, a mounted and driven abrading wheel depending from the carriage, mechanism connected with and for automatically tilting the structure, a support for carrying the shaft of a cultivator disc-gang, said shaft substantially paralleling the direction of shift of said carriage on said structure, and driving mechanism adapted to receive said shaft for rotating the same.

11. In apparatus of the character described, a framing, a tiltable structure supported on the framing constituting a runway for a carriage, a carriage mounted on the structure shiftable therealong, a mounted driven abrading wheel depending from the carriage, a support for carry-

ing the shaft of a cultivator disc-gang, said shaft substantially paralleling the direction of shift of said carriage, and power means to tilt the tiltable structure and to rotate the named shaft.

5. 12. In apparatus of the character described, a framing, a tiltable structure supported on the framing constituting a runway for a carriage, a carriage mounted on the structure shiftable therealong, a mounted driven abrading wheel depending from the carriage, a support for carrying the shaft of a cultivator disc-gang, said shaft substantially paralleling the direction of shift of said carriage, power means to tilt the tiltable structure and to rotate the named shaft, and means to terminate the driving connection of the power means with the said tiltable structure to halt the same.

20. 13. In apparatus of the character described, a framing, a structure pivotally mounted on the framing adapted to be tilted in opposite directions, power means for tilting said structure, a support for supporting the rotatable shaft of a cultivator disc-gang thereon connected to said power means, a carriage carried by and shiftable 25 along the tiltable structure, a rotatable abrading wheel supported on and depending from the carriage in position to act upon any one of the discs of said disc-gang, and means to fix the named tiltable structure with respect to said framing.

30. 14. In apparatus of the character described, a framing, a structure pivotally mounted on the framing adapted to be tilted in opposite directions in a substantially vertical plane, power means for tilting said structure, a carriage shiftable along the structure in a direction at right angles to the tilting movement of the same and itself tiltable with respect thereto, an abrading wheel and a driving shaft therefor carried by and depending from the carriage, a support for 35 the shaft of a cultivator disc-gang having a series of discs thereon, power means to tilt the said structure and to rotate said shaft, the said wheel having a position by which to operate upon any one of said discs, and means mounted on the 40 said carriage and adjustable thereon in the direction of tilting of the latter with respect to the tiltable structure on which it is mounted whereby the said abrading wheel is held by pressure against the surface of a disc being processed.

50. 15. In apparatus for the purpose described, a framing, a substantially horizontal structure mounted on said framing constituting a carriage supported by and shiftable along the same, a rotatable abrading wheel and its shaft extending 55 from said carriage to normally depend therefrom, and said carriage being mounted to swing with respect to said structure and capable of being swung to a position in which said abrading wheel will rotate in a substantially vertical plane, and a member mounted on the said structure to serve 60 as a bearing for the named shaft of the wheel when the latter rotates in said plane, said member normally having a position on said structure free of and distant from said shaft.

65. 16. In apparatus for the purpose described, a platform, a structure mounted upon the same to support the shaft of a cultivator disc-gang, a supporting structure mounted on the platform, a frame pivotally mounted on the said structure 70 constituting a runway capable of tilting with respect thereto in a plane paralleling the planes of the discs of the said disc gang, a source of power shiftable along the runway in a line paralleling the said shaft of the disc-gang, an abrading wheel driven by said power source, driven

mechanism to tilt the runway to move the abrading wheel across the surface of a disc in contact therewith, and driven mechanism operatively connected with the shaft of the disc-gang for rotating the same.

17. An apparatus for the purpose set forth including in its construction a platform, a normally upright supporting structure pivotally mounted at its base upon the platform and having distant from its mounting a recess means for swinging the structure in a vertical plane, said structure when swung downwardly adapted to receive into said recess the shaft of a disc gang, a framing upstanding from the platform, a frame pivotally mounted on the framing adapted to tilt in a plane paralleling the direction of swing of said supporting structure, a rotatable abrading wheel, and means on said frame to carry the wheel and shiftable on said frame in a direction at right angles to the said direction of swing of the named supporting struc-

ture, said wheel adapted when the latter is in its normal upright position to traverse the surfaces of any disc of said disc gang.

ANDREW J. HARTY.
